UNITED STATES PATENT OFFICE

EDWARD H. BERNDSEN AND JOHN L. KELLY, OF ST. LOUIS, MISSOURI
DEODORIZING AND INSECTICIDE ATTACHMENT FOR VACUUM CLEANERS

Application filed November 24, 1931. Serial No. 577,137.

This invention relates to devices for distributing deodorizing and insect destroying substances and pertains particularly to a device designed to be used in association with a blower element.

The primary object of the present invention is to provide a device for attachment to a vacuum cleaner which is adapted to contain a deodorizing and insect destroying chemical which is drawn therefrom by the suction mechanism of the vacuum cleaner and discharged through the vacuum cleaner hose which is coupled to the cleaner machine at the point normally engaged by the dirt receiving bag of the machine.

A further object of the invention is to provide an attachment for the purpose described, which when used with a particular type of deodorant and insect destroyer which occurs in easily broken and volatile crystals, will break up these crystals into a fine state so that they will more rapidly volatilize and be more effective in killing insects and in deodorizing the air into which discharged.

A still further object of the invention is to provide a device for the purpose described which may be easily and quickly applied to or removed from a vacuum cleaner.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a diagrammatic view of a vacuum cleaning machine in side elevation showing the device embodying the present invention applied thereto;

Figure 2 is a vertical longitudinal sectional view through the insecticide holder of the device;

Figure 3 is a sectional view taken on the line 3—3 of Figure 2;

Figure 4 is a sectional view taken on the line 4—4 of Figure 2;

Figure 5 is a sectional view taken on the line 5—5 of Figure 2;

Figure 6 is a sectional view taken on the line 6—6 of Figure 1.

Referring now more particularly to the drawings wherein like numerals of reference indicate corresponding parts throughout the several views, the numeral 1 indicates generally a vacuum cleaner machine of the type commonly used in households and adapted to be moved about from place to place upon the supporting rollers 2. The fan casing of the present machine is indicated by the numeral 3 and the inlet thereto is through the nozzle 4, to which is normally attached the suction or pick-up nozzle (not shown) of the machine. The outlet nozzle of the blower or fan casing 3 is indicated by the numeral 5 and this nozzle, as well as the nozzle 4, upon the majority of machines of this character, is provided with lugs 6 for engagement in slots 7 formed in the inner wall of a collar 8 to which the flexible hose 9, which is supplied with such machines, is connected. Ordinarily the outlet nozzle 5 of the fan casing has attached thereto a dirt receiving container or bag but for the use of the attachment embodying the present invention this bag is removed and the hose is coupled with this nozzle, as will be hereinafter more fully described. Also, for the use of the present attachment the pick-up nozzle normally connected with the inlet nozzle 4 of the fan housing, is removed and a part of the present device is attached in its place.

The device embodying the present invention consists of three elements which are indicated by the numerals 10, 11 and 12, although it is not essential that all of these elements be used together at all times.

The element 10 consists of an elongated casing 13 preferably of cylindrical formation, one end of which will hereinafter be referred to as the inner end, is formed to provide the collar 14 which receives

the nozzle 4, this collar being supplied with the necessary slots for the reception of the lugs on the collar to hold the cylinder in the position shown.

- 5 Inwardly of the inner end of the cylinder 13, preferably about one inch therefrom when the cylinder is approximately seven inches long, is a screen wire partition 15 which is spaced at its lower edge from 10 the lower part of the cylinder, thus leaving the unscreened entrance opening 16. At one side of the opening 16 the cylinder has secured to the wall thereof guide elements 17 and disposed between the screen and 15 these guide elements is a gate plate 18 which may be moved upwardly between the guides and the screen to uncover the opening 16.

The movement of this gate 18 is controlled by a screw 19 which passes downwardly 20 through the top of the cylinder and engages a nut 20 carried by the gate. This screw 19 may be swivelly mounted in the wall of the cylinder so that upon rotating the same through the medium of the head 21 upon 25 the outer end thereof the nut 20 will be caused to ride up thereon and at the same time raise the gate.

Adjacent the other or outer end of the cylinder 13 is an air inlet control disk 22, 30 the upper half of which is imperforate as indicated at 23, while the other half thereof is formed of wire screen as indicated at 24. This screen may be readily removed from the end of the cylinder to permit of the introduction of a suitable deodorizing and insecticidal chemical of any suitable character, the use of the chemical known as paradi-chlorbenzene.

When the device is not in use the outer 40 end thereof may be closed by the cap 25 which has a flange portion 26 which threadably engages about the end of the cylinder.

The element 11 is in the form of a cylinder which has a collar 27 at one end formed 45 to couple onto the outlet nozzle 5 of the blower casing and its other end 28 is formed for extension into the collar 8 to which the hose 9 is attached. This end 28 is provided with lugs similar to lugs 6 on the nozzles 4 and 5, for engagement in the slots of the 50 collar 8. Within this cylindrical element 11, which as shown is designed to be interposed between the hose 9 and the discharge nozzle 5, are two partitions 29 of relatively fine mesh screen wire.

The element 12 is also in the form of a cylinder and this is of the same or constant diameter throughout and is intended to snugly engage in the hose 9 in the manner 60 shown.

This cylinder element 12 also has a pair of screen wire partitions therein like the cylinder element 11, these screen wire partitions being indicated by the numerals 30.

65 In the use of the present attachment for

the killing and controlling of moth infestation in furniture, clothes, etc., the proper dry chemicals are placed in the container cylinder 13 by removing the cap 25. With the elements 11 and 12 in the positions illustrated and the gate element 18 raised to the proper height to permit the desired amount of crystals to be sucked from the container for discharge through the hose 9, the machine is started and the hose directed as desired for discharging the chemical into furniture, clothes or elsewhere. As the chemicals are drawn from the container cylinder 13 they will be forced through the fine wire mesh partitions of the cylinders 11 and 12 and broken up into a fine powder so that the volatilization thereof can take place rapidly. The major portion of the chemical is therefore discharged from the hose 9 as a gas while some of the unvolatilized powder will be discharged also.

For the eradication of roaches and other insect pests and for deodorizing, it is not necessary to use the elements 11 and 12 as these are only intended for use in association with chemicals which come in crystal form such as the chemical previously referred to.

Having thus described the invention, what is claimed is:—

1. In a mechanism of the character described, a suction fan and a casing enclosing the same having an inlet and an outlet, a disinfectant chemical container having an inlet opening and an outlet opening, means for detachably securing the container outlet opening over said casing inlet, a screen member in the container forming a partition wall before the outlet therefor, a second member in the container forming a partition before the inlet therefor, said second member having a screen in its lower part, the lower part of the first screen being open, a shiftable closure for the opening of said first screen, and a tube connected at one end with the outlet of said casing, the said container having a volatile substance therein between said members to be taken up by air drawn through the container by the fan and discharged through said tube.

2. In a mechanism of the character described, a suction fan and a casing enclosing the same having an inlet and an outlet, a container having an inlet and an outlet, means for securing the outlet of said container over the inlet of the casing, a removable closure member for the inlet of the container, a screen partition within said container and overlying the outlet thereof, said screen having a portion thereof removed, a gate mounted for sliding movement adjacent said screen to normally close the removed portion thereof, a screw member extending through the wall of the container and engaging said gate for effecting its movement to open or closed position, and a tubu-

- lar body connected with the outlet of the casing, said container being designed to receive a substance which is drawn therefrom by the suction fan into the casing and discharge through said tube. 3. In a mechanism of the character described, a suction fan and a casing enclosing the same having an inlet and an outlet, a cylindrical container open at each end and formed to have one end engaged over the inlet of the casing, a removable cap for the other end of the container, a disk-like body removably positioned in said container at the end adjacent the cap and having a foraminous portion, a wire screen partition within the container adjacent the end remote from the cap and having an opening through the lower part thereof, a plate member normally closing said opening of the screen partition, guide means for maintaining said plate in position and permitting its sliding movement over the face of the screen to open or close the opening, a screw extending through the wall of the container and engaging said plate and operating when rotated to shift the plate, and a tube connected with the outlet of the casing, the said container being designed to receive a substance which is drawn by the suction fan from the container and discharged through the tube. 4. In a mechanism of the character described, a suction fan and a casing enclosing the same having an inlet and an outlet, a container having an inlet and an outlet, means for securing the outlet of the container over the inlet of the casing, a cylinder detachably connected at one end with the outlet of the casing, a cap detachably connected with the other end of the cylinder and formed to provide a tubular extension, screen members within said cylinder, and a tube connected at one end with said reduced tubular extension of the cylinder cap, the said container being designed to receive a crystal disinfectant chemical which is drawn therefrom by the suction fan into the casing and discharged from the casing into said cylinder and broken up in its passage through the screens of the cylinder to the tube. 5. In a mechanism of the character described, a suction fan and a casing enclosing the same having an inlet and an outlet, a disinfectant chemical container having an inlet and an outlet, means for detachably securing the outlet of said container over the casing inlet, a tube, means for connecting one end of the tube with the outlet of the casing, a cylinder of a diameter to frictionally engage within the tube, the cylinder being completely housed in the tube, and screen partitions in said cylinder, said container being designed to receive a disinfectant chemical which is drawn therefrom through the casing by the fan and discharged into the air through the tube and finely broken up in its passage through the screens of the cylinder. In testimony whereof we hereunto affix our signatures.
